UNITED STATES PATENT OFFICE

JOHN T. NEEDHAM, OF NORTH PLAINFIELD, NEW JERSEY

CARRIER FOR PNEUMATIC-DISPATCH TUBE SYSTEMS

Application filed November 8, 1928. Serial No. 318,031.

An important object of the present invention is to provide a carrier with a thoroughly satisfactory ejector device to facilitate the removal of its contents.

5 Other objects will appear hereinafter.

In the drawings, Fig. 1 is a longitudinal sectional view of the carrier, taken on the line 1—1 of Fig. 3, the carrier being closed:

Fig. 2 a transverse section taken on the line 2—2 of Fig. 1;

Fig. 3 a transverse section taken on the line 3—3 of Fig. 1;

Fig. 4 an enlarged fragmentary section taken on the line 4—4 of Fig. 1;

15 Fig. 5 a detail perspective view of the guide forming part of the guide of the ejector device; and

Fig. 6 a view similar to Fig. 1, showing the carrier opened and the ejector plunger drawn 20 outwardly.

The carrier structure includes a body or barrel 1 which consists of a tube of hard fiber or other suitable material. The tube is closed at one end by an external cup 2, the annular 25 flange of which is riveted to the carried body as at 3. A felt buffer head 4 is riveted to the outer face of the cup 2. The opposite end of the barrel is open and is reinforced by an external sleeve 1' riveted to it.

30 To the inner side of the carrier and extending longitudinally thereof is rigidly secured a tube or channel 5. This tube is preferably secured in place by tongues 6 formed thereon and passed through the body of the carrier.

35 A rod 7, preferably formed of a strand of stiff wire, extends through the channel and slidably through a guide sleeve 8 fixed in the channel near the outer end thereof. Inwardly of sleeve 8 a collar 9 is rigidly secured to the rod 7, and between said collar and sleeve is interposed a spring 10 which tends to force 40 the locking rod toward the closed end of the carrier. Rigidly secured to the rod near its outer end, beyond the sleeve 8, is a guide sleeve

45 11 which is slidable within the upper end of channel or tube 5. At its outer end the rod is formed into an arch 12 and with a coil 13 at the base of the arch, said coil being adapted to be disposed within the carrier and form 50 a skeleton closure or clip for the purpose

of retaining the contents in the carrier. The rod 7 is rotatable in the sleeve 8 and may be drawn outwardly against the tension of the spring 10 by grasping and pulling the arch 12. When the holding clip coil has been completely withdrawn from the carrier, the rod may be rotated to carry the retaining coil beyond the edge of the carrier as indicated in Fig. 6. The rod may be then released to permit the spring 10 to draw the coil into engagement with the edge of the carrier and thereby hold the retaining means in their open position. The sleeve 11 slidably fits in the upper end of the guide channel 5 and is adapted to bottom against the fixed sleeve 8 65 to limit the inward movement of the rod and properly position the clip in its closed position. In the latter position of the clip the arch is substantially flush with the open end of the barrel 1.

55 Mounted upon the inner wall of the barrel, alongside the channel 5, is a guide tube or channel 14 similar to channel 5 and of almost equal length. Its inner end is adjacent the end cup 2 of the barrel and its outer end terminates slightly inwardly of the outer end of channel 5. It is held in place by integrally formed bendable tongues 15 which are passed outwardly through the barrel. A sleeve 16 is 70 mounted in the upper end of the channel 14 and serves as a guide to slidably support a slender plunger rod 17 which extends through the channel for most of the length of the latter. This rod is preferably formed

75 of stiff wire. The guide channel 15 is formed with an elongated slot 18 which extends between the sleeve 16 and the inner end of the channel. The inner end of the rod is bent inwardly at right angles as at 19, and extends through the slot 18 and across the inside of the barrel. A flat sheet metal disk 20 is secured to the extension 19 and forms the plunger head. Its diameter is almost equal to the internal diameter of the barrel and its peripheral edge is notched to clear the rivets 80 3 and the channels 5 and 14. The outer end of the plunger rod 17 extends beyond the fixed sleeve and is bent to form an arcuate handle 21. The latter is disposed close to the inner wall of the barrel and conforms substantially 85 to the shape of the barrel. The sleeve 16 is 90 secured to the barrel by rivets 22. The sleeve 16 is 95 secured to the barrel by rivets 22. The sleeve 16 is 100 secured to the barrel by rivets 22.

to the inner curvature thereof. Rigidly secured to the rod 17 near the bend 19 is a sleeve or collar 22, and a light compression spring 23 encircles the rod and is interposed between said sleeve and the fixed guide sleeve 5 16. Spring 23 tends to press the plunger inwardly and hold the plunger head 20 at its innermost position adjacent the cup 2. The inward movement of the plunger is limited by contact of the bend 19 with the lower end of 10 the slot 18.

When the plunger is in its innermost or normal retracted position the carrier may be filled and the spring-pressed clip 13 snapped to closed position to retain the contents. The 15 closure plunger and the ejector plunger are so relatively proportioned and mounted that when the former is in its closed position the arcuate handle 21 of the ejector directly underlies the coil of the clip 13 and the latter 20 conforms to the curvature of the handle and covers it. The clip thus protects the ejector handle and prevents operation of the ejector and possible crushing of the contents when 25 the carrier is closed. When the contents are to be removed the arch 12 of the clip is grasped and the clip is drawn outwardly against the resistance of spring 10, swung to a non-obstructing position and left to rest 30 upon the end edge of the carrier. This exposes and frees the ejector handle which is grasped and pulled outwardly through the open end of the carrier against the resistance of spring 23 to draw the plunger head 20 outwardly. The latter serves as a pusher member 35 to shove the contents partly through the open end of the carrier so that they may be readily grasped and removed. The slot 18 in the guide channel 15 permits the plunger head to move to a position substantially mid- 40 way the length of the carrier. When the handle 21 is released the spring 23 snaps the ejector plunger back to normal retracted position. The plunger head substantially fits the interior of the carrier so that it prevents 45 the plunger rod from rocking and holds the handle 21 against lateral displacement. Consequently the handle will not catch upon the edge of the carrier when it is released for the 50 retraction of the ejector, and when the ejector is in normal retracted position the handle will be held snugly against the inner wall of the carrier so that it will not obstruct the charging of the carrier. The entire ejector occupies 55 a protected position within the carrier and is so designed that it takes up a minimum amount of space therein. It is thoroughly efficient and reliable and greatly speeds up the handling of the carriers in a pneumatic 60 dispatch tube system.

What I claim is:

1. A carrier for a pneumatic dispatch tube apparatus, comprising a tubular body closed at one end and open at the opposite end to 65 receive and discharge the tube contents; man-

ually operable means carried by the tubular body to eject the contents; and means carried by the body to automatically retract said ejector means to normal position when it is released.

2. A carrier for a pneumatic dispatch tube apparatus, comprising a tubular body closed at one end and open at the opposite end to receive and discharge the carrier contents; means carried by the tubular body to eject the contents; and closure means carried by the body, shiftably mounted to open and close the latter and adapted to prevent operation of the ejector means when in closed position and thereby prevent crushing of the contents. 70

3. A carrier for a pneumatic dispatch tube apparatus, comprising a tubular body closed at one end and open at the opposite end to receive and discharge the carrier contents; means normally carried entirely within the tubular body to eject the contents; and closure means shiftably carried by the body to open and close the latter, and adapted to prevent operation of said ejector means when closed and thereby prevent crushing of the 80 contents. 85

4. A carrier for a pneumatic dispatch tube apparatus, comprising a tubular body closed at one end and open at the opposite end to receive and discharge the carrier contents; manually operable means normally disposed entirely within the tubular body to eject the contents; means to automatically restore said ejector means to normal position within the body after an operation thereof; and closure 95 means shiftably carried by the tubular body to open and close the latter, and adapted to prevent operation of said ejector means when closed, and thereby prevent crushing of the 100 contents. 105

5. In a carrier for a pneumatic dispatch tube apparatus, means carried by the carrier to eject the contents thereof, said ejector means being normally disposed entirely within the carrier; and closure means shiftably carried by the carrier to open and close it and adapted when closed to prevent the operation of the ejector means and thereby prevent crushing of the contents. 110

6. In a carrier for a pneumatic dispatch tube apparatus, manually operable means carried by the carrier to eject the contents thereof; means to automatically restore said ejector means to normal position after an operation thereof; and closure means shiftably carried by the carrier to open and close the latter and adapted to prevent operation of the ejector means when closed. 115 120

7. A carrier for a pneumatic dispatch tube apparatus, comprising a tubular body closed at one end and open at the opposite end to receive and discharge the carrier contents; a reciprocably mounted ejector normally disposed entirely within the tubular body and including a slender arcuate operating han- 125 130

5 dle normally disposed a short distance within the open end of the tubular body along the inner wall thereof and conforming to the curvature of the wall, said handle being
 10 adapted to be pulled outwardly through the open end of the carrier to operate the ejector; and means holding the handle against lateral displacement and preventing its catching upon the open end of the carrier on its
 15 return movement.

10 8. A carrier for a pneumatic dispatch tube apparatus, comprising a tubular body or barrel closed at one end and open at the opposite end to receive and discharge the barrel
 15 contents; an ejector plunger normally disposed entirely within said barrel and comprising a pusher member normally at the closed end of the carrier, and a slender operating rod attached to the pusher member,
 20 extending longitudinally along the inner wall and provided with a slender handle normally adjacent the open end of the barrel and disposed against the inner wall thereof; and guide means mounted upon the inner wall of
 25 the barrel and supporting the plunger rod for reciprocation, whereby the pusher member may be moved outwardly by the handle and rod to eject the contents of the barrel, the pusher member holding the rod against
 30 rocking movement by contact with the inner wall of the barrel and preventing lateral displacement of the handle.

35 9. A carrier for a pneumatic dispatch tube apparatus, comprising a tubular body or barrel closed at one end and open at the opposite end to receive and discharge the barrel contents; an ejector plunger normally disposed entirely within said barrel and comprising a pusher member normally at the closed end of
 40 the carrier, and a slender operating rod attached to the pusher member, extending longitudinally along the inner wall and provided with a slender handle normally adjacent the open end of the barrel and disposed
 45 against the inner wall thereof; guide means mounted upon the inner wall of the barrel and supporting the plunger rod for reciprocation, whereby the pusher member may be moved outwardly by the handle and rod to
 50 eject the contents of the barrel, the pusher member holding the rod against rocking movement by contact with the inner wall of the barrel and preventing lateral displacement of the handle; and a spring within the
 55 barrel to automatically retract the plunger.

10 10. A carrier for a pneumatic dispatch tube apparatus, comprising a tubular body or barrel closed at one end and open at the opposite end to receive and discharge the barrel contents; an ejector plunger normally disposed entirely within the said barrel and comprising a pusher member normally at the closed end of the carrier, and a slender operating rod attached to the pusher member, extending
 15 longitudinally along the inner wall and pro-

vided with a slender handle normally adjacent the open end of the barrel and disposed against the inner wall thereof; guide means mounted upon the inner wall of the barrel and supporting the plunger rod for reciprocation, whereby the pusher member may be moved outwardly by the handle and rod to eject the contents of the barrel, the pusher member holding the rod against rocking movement by contact with the inner wall of the barrel and preventing lateral displacement of the handle; a spring within the barrel to automatically retract the plunger; and a skeleton closure member formed of looped wire shiftably carried by the barrel to open and close the latter and adapted when closed to overlie the arcuate plunger handle and prevent operation of the plunger.

In testimony whereof I hereunto affix my signature.
